[57] ABSTRACT

An improved means for compacting staple fibers into firm engagement with the pins of a pin elevator includes a multiplicity of flexible curved strips mounted in a circumferentially offset manner on a rotatable member adjacent to and extending horizontally across the width of the upward moving reach of the pin elevator.

FIG. 2

LOADER FOR PIN ELEVATOR

BACKGROUND OF THE INVENTION

This invention is concerned with the feeding of staple fibers and more particularly with improved means for the uniform loading of low-density, turgid pneumacel fibers onto the pins of a pin elevator.

Use of a pin elevator to feed staple fibers is well known. In operation, a series of horizontal slats, each bearing a multiplicity of upwardly angled, sharpened pins, on a continuous belt is driven upwardly past a feed stock of loose staple fibers urged toward the pins by a slow-moving horizontal belt. The pins carry a lightly tangled mass of fibers upwardly past a spiked stripper roll which removes those fibers which project more than a certain distance beyond the slats and recycle them to the feed stock. Thus, as the belt carrying the slats moves across the top roll a fairly uniform amount of fibers is delivered by the pins to a doffer roll which removes substantially all the fibers and directs them to the subsequent stage of processing.

The pin elevator is not considered to be a highly accurate metering device and subsequent textile operations are relied on to compensate for unevenness in both its distribution across the width of the elevator and its total delivery per small unit of time. The lack of "cross-machine" and "along-the-length" uniformity in delivery is largely due to (1) practical inability to provide a feed stock of uniform structure (resulting in non-uniform pickup by the pins), (2) the tendency of the fiber to clump and for the clump to inhibit access of fibers to the pins just below the moving clump (leaving a sparse area of fiber pickup) and (3) nonuniform stripping, due at least in part to the nonuniform engagement of the fibers on the pins of the elevator as they approach the stripper roll.

The fundamental bases for nonuniform delivery are exaggerated in the handling of buoyant, turgid pneumacel fibers, which tend to spring away from any tenuous engagement with the pins. The special requirements for feeding pneumacel fibers are recognized in U.S. Pat. No. 3,717,904 and a compaction roll is provided thereby to make a more compact mat of the fibers on the pin elevator. While the compaction roll offers an advantage over the art, it is apparent that further improvement is necessary to the objective to deliver a uniform amount of pneumacel fiber with respect to both machine- and cross-direction distribution and rate. A means to compensate for the sparse area of pickup immediately following a picked-up clump of fibers is still needed.

SUMMARY OF THE INVENTION

In an elevator for staple fibers including an endless driven belt having an upward moving reach with pins attached thereto for moving said fibers upward from a source of fiber stock presented to the pins the improvement comprising: a driven rotating elongated member positioned adjacent said upward reach, said member extending substantially horizontally across the full width of the upward moving reach of said belt; and a plurality of flexible curved strips extending radially from said member. The flexible curved strips are mounted in a circumferentially offset manner but substantially contiguously in the axial direction on the rotating member. The rotating member is driven in the

direction to present the convex sides of said curved strips to the fibers tenuously held by the pins of said elevator so as to urge said fibers downwardly into firmer and more uniform engagement with said pins.

BRIEF DESCRIPTION OF THE DRAWING

FIG. 1 is a schematic side elevation view of portion of a conventional pin-elevator feeder as modified by inclusion of one embodiment of the apparatus of this invention; and

FIG. 2 is a schematic front elevation view of the rotatable assembly of flexible curved strips as seen from 2-2 in FIG. 1.

DETAILED DESCRIPTION OF THE ILLUSTRATED EMBODIMENT

Referring to the drawing, feed apron 10 urges staple fiber feed stock 12 from source not shown toward pin elevator 13, which includes an endless belt having an upward moving reach 13a. The pins 14 on pin elevator 13 engage the nearest fibers and raise them past compression rotor 15, flexible strips 16 of which urge the fibers into firmer, more uniform engagement with the pins. As the engaged light tangle of fibers is brought past stripper roll 17, those projecting more than a predetermined distance above the pins are removed and returned to the feed stock. The fibers carried over roll 18 by the belt are discharged by means not shown to the subsequent stage of processing.

In this embodiment, flexible strips 16 are made of stainless spring steel 0.031 inch thick and 3 inches wide and are curved in a convex surface 16a at their tip ends. They are assembled in alternating, 90°-apart orientations into a hub or compression rotor 15 consisting of four angle members, adjacent strips being very close or in actual contact with each other, and the entire assembly being rigidly bolted together. The rotating member may be positioned up to 12 inches above the normal working level of the staple feed stock to be presented to the pins and at a distance from the upward moving reach of the elevator to provide a clearance of from $\frac{1}{8}$ to 6 inches between the tips of the strips and the tips of the elevator pins. The rotating member 15 is driven by means not shown at about 50 rpm and in the direction to present the convex surfaces 16a to the fibers held by pins 14 on the elevator. Pin elevator 13 is driven at a rate of about 60 feet per minute.

Baffle 19 is an optional feature which has been found of value in this particular embodiment. It is a 30-inch high sheet of noncorrodable metal of a thickness to result in good rigidity when mounted across the entire width of the space above the fiber feed stock and about 6 inches away from the tips of the flexible strips. The baffle curves somewhat below rotor 15 toward the upward moving reach of belt 13 and serves to retain an excess of fiber in the vicinity of the rotating strips and to assure availability of fiber to be pressed into the sparse areas on the pin elevator. With this baffle in place, the flexible strips are seen to be substantially immersed in a bed of tumbling fiber.

It will be obvious that alternative arrangements of the strips around the hub, alternative dimensions of the strips and adjustments in relative speeds and spacings are within the spirit and scope of this invention if the arrangement arrived at is capable of repetitive urging of staple filaments into more uniform and firmer engagement with the pins of a pin elevator.

It has been observed that the rolling action imparted to fibers at the juncture of feed apron 10 and the pinned slats of pin elevator 13 results in clumps, or rolls, of fibers which finally are picked up by a section of pins. As this clump is moved upward through the fiber feed stock, it temporarily impedes progress of additional feed stock toward the pins, leaving them empty or only sparsely loaded. The compression roll of U.S. Pat. No. 3,717,904 was effective in urging such clumps into firmer engagement but was not capable of adding fiber to the sparse areas below them. The apparatus of this invention, however, appears to effect a gentle rearrangement of fibers on the pins by urging loosely held outer fibers from the larger clumps downwardly and into firm engagement with any pins as yet incompletely filled.

What is claimed is:

1. In an elevator for staple fibers including an endless driven belt having an upward moving reach with pins attached thereto for moving said fibers upward from a source of fiber stock presented to the pins the improvement comprising: a driven rotating elongated member

positioned adjacent said upward reach, said member extending substantially horizontally across the full width of the upward moving reach of said belt; and a plurality of flexible curved strips extending radially from said member, said strips having convex surfaces at their ends, said surfaces being presented to the fibers held by the pins on said upward reach; and a fixed baffle positioned adjacent said member, said member being between said upward moving reach and said baffle, said baffle curving below said member toward said upward moving reach for retaining staple fibers in the vicinity of said curved flexible strips.

2. The elevator of claim 1, said strips being mounted in a circumferentially offset manner and substantially contiguously in the axial direction along the member.

3. The elevator of claim 1, said member being positioned a distance of up to 12 inches above said source, said strips having curved outward ends, said ends being spaced from said upward reach a distance of from $\frac{1}{8}$ inch to 6 inches.
